(57) **CLAIM**

The ornamental design for a mobile telephone, as shown.

DESCRIPTION

FIG. 1 is a front and left side perspective view of a mobile telephone showing our new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof;

FIG. 8 is a front elevational view showing the folding condition and the camera was rotated thereof;

FIG. 9 is a right side elevational view showing the folding condition thereof;

FIG. 10 is a top plan view showing the folding condition thereof; and,

FIG. 11 is a rear elevational view showing the folding condition and the camera was rotated thereof.
